THOMAS HENRY KANE, OF YOUNGSTOWN, OHIO, ASSIGNOR TO TRUSSSED CONCRETE STEEL COMPANY, OF DETROIT, MICHIGAN, A CORPORATION OF MICHIGAN.

PROTECTING-PLATE FOR THE EDGES OF CONCRETE CONSTRUCTIONS.

1,111,839.

Specification of Letters Patent. Patented Sept. 29, 1914.

Application filed January 19, 1914. Serial No. 812,879.

To all whom it may concern:

Be it known that I, THOMAS H. KANE, a citizen of the United States, and a resident of Youngstown, in the county of Mahoning and State of Ohio, have invented a new and Improved Protecting-Plate for the Edges of Concrete Constructions, of which the following is a specification.

This invention relates to plates or bars 10 adapted to protect the edges of concrete roadways at each side of the expansion-joints therein, and its object is to provide a cheap and reliable expansion-joint protector which will prevent the forming of a 15 groove or rut in the surface in the concrete along the reinforcing plates.

This invention consists of a plate of any desired depth and thickness, whose length is preferably the width of the roadway and 20 whose upper edge conforms to the curvature of the roadway, if any, which plate is provided with any desired means to secure it to the concrete of the roadway, and which is provided with an over-hanging ledge along 25 its upper edge on the side toward the concrete to which it is attached.

In the accompanying drawings Figure 1 is a perspective showing the improved reinforcing plate secured in position to the 30 end of a section of roadway. Figs. 2, 3 and 4 are end views of plates adapted to be used for the purpose of reinforcing roadways. Fig. 5 is a perspective of a section of reinforcing plate after the connectors have been 35 bent to operative position.

Similar reference characters refer to like parts throughout the several views.

Probably the best pavement, cost considered, so far evolved for roads and streets 40 subjected to medium weight traffic, is a good grade of concrete. Breaks or cracks must arbitrarily be made across the roadway or else irregular, unsightly cracks will develop naturally, due to the fact that concrete contracts and expands from the action of both temperature and moisture. The pavement will either pull itself apart or else must be provided with expansion joints placed at intervals so as to allow this 45 constant movement without damage to the mass. The crack or joint thus formed is, unless properly protected, the weakest point of the roadway, and many devices have been suggested for the protection or armoring of 50 the roadway along these joints. The usual 55

method is to secure a narrow, flat plate to each portion of the roadway in such a manner that the upper edge of the bars or plates will be flush with the roadway. Asphalt, tar or other elastic material is then poured 60 into the space between these plates and the concrete forming the two portions of the roadway.

It has been found that under the action of traffic, the edge of the concrete next adjacent the reinforcing plates chips off and crumbles continually, the groove becoming larger until quite a rut is formed. This results in the armoring plate being struck 65 blows of considerable intensity until the 70 plate finally becomes loosened. By preventing the first formation of this small groove, the damage may be entirely avoided. I have found that by forming the protecting plates with an over-hanging ledge so 75 that no sharp corner will be formed on the concrete, the first chipping off is prevented and a smooth, even surface will always be had.

The exact cross section of the plates used 80 for reinforcing the upper edges of the roadway along the expansion joints, and especially their widths and thicknesses, may be varied, as well as the means provided for securing this plate to the concrete. I prefer 85 the construction shown in Figs. 1, 3 and 5. In Fig. 5 a plate 1 has an over-hanging ledge 2 having its lower face concave, and is provided with arms 3 having bifurcated ends constituting transverse members 4, all 90 of which are sheared out of the bar, thus forming slots 5 through which the concrete of the roadway may extend and assist in holding the reinforcing bar in place. In Figs. 1 and 3 the plate 1 is shown with a 95 reinforcing flange 7 along its lower edge which will assist in stiffening the plate against vertical distortion. Fig. 1 shows concrete 6 and a sheet 10 of some elastic material to fill the space between the ends of 100 adjacent sections of roadway.

Instead of forming the reinforcing plate with an overhanging ledge 2, it may be formed as shown in Fig. 4 and be constituted by a body 8 and a laterally extending 105 flange 9, the edge of the flange being beveled so as to avoid sharp corners on the concrete.

In some localities the expansion and contraction of the roadway may be very small 110

because of the slight changes of temperature. In such cases a single reinforcing plate, bent as shown in Fig. 2, may be secured to both of the adjoining ends of two sections of roadway. The space between the two sides 11 of the plate can then be filled with coal tar or asphalt. The overhanging ledges 12 will protect the two upper edges of the adjacent sections in the 10 manner heretofore described.

It will be evident that many changes in the construction of the reinforcing plates can be made to meet the various requirements of road building without departing 15 from the spirit of my invention set forth in the claims. It will be evident that while these plates are primarily adapted for reinforcing the upper edges of roadways, that they are also adapted for reinforcing the 20 corners of any other concrete constructions, such as curbs, sidewalks and steps.

I claim:

1. A reinforcing plate for the edge of a body of concrete comprising a flat plate, 25 means to secure this plate against the side of the body of concrete with its outer face vertical, and an over-hanging ledge formed along the upper edge of the plate on the side next to the concrete to protect the edge of 30 the concrete, the lower edge of said ledge being beveled so as to ensure an obtuse angle on the concrete, and the entire top of the plate being flush with the concrete and forming a right angle with the outer face of 35 the plate.

2. A reinforcing plate for the edges of expansion joints between sections of concrete roadways, comprising a plate having a stiffening rib along its lower edge and a short over-hanging ledge along its upper 40 edge on the side next to the concrete, said ledge having a flat upper surface in the plane of the roadway and a beveled lower surface that joins the flat upper surface along a sharp edge, and means for securing 45 the reinforcing plate against the side of the body of concrete, the exterior of the plate being flat and vertical and forming a right angle with the upper surface of the ledge.

3. A reinforcing plate for the edges of 50 expansion joints between sections of concrete roadways, comprising a vertical plate having a flat body portion with a flat outer side and a short over-hanging ledge formed along its upper edge on the side next to the 55 concrete, said ledge having a flat upper surface in the plane of the roadway forming a right angle with the outside of the plate, and an inclined lower surface merging with the flat upper surface at an acute angle, and 60 means for securing the reinforcing plate against the side of the body of the concrete.

In testimony whereof I have signed this specification in the presence of two subscribing witnesses.

THOMAS HENRY KANE.
